UNITED STATES PATENT OFFICE.

WILLIAM FRANK WILLIAMS, OF MIAMI, ARIZONA.

MULTIPLE-SIGNATURE MACHINE.

1,268,523.

Specification of Letters Patent. Patented June 4, 1918.

Application filed June 19, 1917. Serial No. 175,616.

To all whom it may concern:

Be it known that I, WILLIAM F. WILLIAMS, a citizen of the United States, and a resident of Miami, in the county of Gila and State of Arizona, have invented a new and Improved Multiple-Signature Machine, of which the following is a full, clear, and exact description.

This invention relates to that class of devices covered by Letters Patent of the United States issued to me on the 9th day of March, 1915, No. 1,131,451, and has particular reference to improved facilities for transmitting the motion of the hand to all of the pens of the system so that the motion of the master pen will be faithfully reproduced by all of the auxiliary pens.

Among the objects of this present improvement therefore is to provide a multiple signature machine in which there are arranged a plurality of carriages mounted for independent movement at right angles to one another upon anti-friction bearings especially designed for this type of machine.

Another object of the invention is to provide improved facilities for more delicately adjusting the elevation and control of the pen bar, or the bar to which all of the pens are secured for similar movement.

Another object of the invention is to provide improved facilities for doubling the number of signatures which may be formed successfully and simultaneously.

A still further object is to provide an improved combined holding and guiding device for direct coöperation with the documents to be signed.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view of the principal parts of one form of my improvement.

Fig. 2 is a left side elevation of the same.

Fig. 3 is an end elevation adjacent to the operator, a fragment of the base being

broken away to disclose the length of one of the transverse carriages.

Fig. 4 is an enlarged sectional detail of the base in the line 4—4 of Fig. 1.

Fig. 5 is a detail view of one of the ball spacers for the transverse carriages.

Fig. 6 is a perspective view of one end of the main carrier frame and the carriage secured thereto.

Fig. 7 is a vertical transverse section on the line 7—7 of Fig. 8.

Fig. 8 is a longitudinal detail view partly in section on the line 8—8 of Fig. 7.

Fig. 9 is a vertical transverse section on the line 9—9 of Fig. 1.

Fig. 10 is a detail view of the master pen and means for manipulating the same.

Fig. 11 is a detail perspective view of one of the pen brackets secured to the pen bar.

Fig. 12 is a plan view of a part of a modified form of the invention; and

Fig. 13 is a vertical transverse sectional detail on the line 13—13 of Fig. 12.

Referring now more particularly to the drawings I show at 15 a base of suitable size and form to accommodate the improvement to the operator for practical operation. As will be understood from Figs. 1 and 4 the base is provided with transverse slots 16 and 17 in each of which are arranged a pair of upper and lower V-shaped track ways 18 and 19 lying in the same vertical plane and secured to the horizontal flanges of a channel bar 20.

21 indicates as a whole the main carrier frame comprising a straight lower bar 22 and an upper bar 23, the ends of the latter being bent downwardly and rigidly secured to or adjacent to the ends of the bar 22 as indicated at 24. These bars as well as the other principal parts of the frame work are made preferably of tubular metal for the sake of stiffness and lightness. The end of the bar 23, however, where it is connected to the lower bar is substantially semi-tubular.

In each of the slots 16 and 17 and co-operating with the pair of track ways 18 and 19 therein is a carriage indicated as a whole at 25, the same comprising a bar 26 having upper and lower V-shaped grooves 27 and 28 lying in the same plane as the grooves 18 and 19 and held from lateral movement from the plane thereof by means

of a plurality of anti-friction rollers shown as balls 29. This bar 26 is made preferably of two parts for the sake of simplicity, cheapness and lightness of construction, secured together by rivets 30 or their equivalent. The balls 29 are held in place with respect to the other parts of the carriage 25 and spaced from one another in their respective grooves 27 and 28 by means 5 of a spacer 31 shown as in the form of a channel member having upper and lower flanges 32 formed with as many holes 32' as there are balls and through which holes the balls project. This spacer is held in 10 place loosely by the balls. A hanger 33 is secured rigidly at its upper end to the end of the carrier frame 21 and at its lower end to the central portion of the carriage 25. It will thus be seen that the carrier 15 frame 21 is held always in a vertical plane perpendicular to the vertical planes of the track ways in which the carriages 25 operate. The carriages being of considerable length prevent all possibility of the 20 main carrier frame tilting in its vertical plane as well as all possibility of twisting or deviation in a plane parallel to the base, although it is free to move bodily laterally of the base being so carried by the carriages 25 rolling freely in their respective 25 planes along the respective pair of guideways in the slots 16 and 17. In other words the carrier frame 21 may occupy any one of an indefinite number of vertical planes parallel to one another and perpendicular 30 to the planes of the carriages. Thus provision is made for free movement of the pen devices laterally of the base.

The main portions of the bars 22 and 40 23 are horizontal and parallel to each other. The upper portion of the bar 22 carries a V shaped track way 34 and the upper bar 23 has adjustably suspended therefrom a similar track way 35, the means of suspension including a series of screws 36 extending upwardly into or through the upper bar 23 and having milled nuts 37 lying in a horizontal plane in slots 38 cooperating with said screws. These track 45 ways are close to each other and lie in the same vertical plane representing the plane of the carrier frame. The track ways 34 and 35 may be continuous or made in sections as indicated in Fig. 2. Adjustment 50 means at 37 provides for delicacy of adjustment so as to give perfect freedom of movement of the parts between the same without lost motion or looseness.

Coöperating with the guideways 34 and 60 35 is a main carrier, indicated in Figs. 2 and 8 as comprising a pair of composite heads 39 and 40 similar in character or construction to the carriages 25 and each including a spacer 41 for a series of balls 65 42 which make anti friction connection be-

tween the heads and the track ways 34 and 35 and provide for free longitudinal movement of the carriage in the carrier frame. To each of the heads is secured a lug 43 and in these lugs is journaled a rock shaft 70 44 having squared ends 45 just on the outside of the lugs 43. Each end of the rock shaft which passes through the lug 43 is reduced in diameter and surrounded by a sleeve 46 about which is coiled a spring 47 75 one end of which is secured to the adjacent head 39 or 40 and the other end is secured to a milled disk 48 carrying a pawl 49 coöperating with the teeth of a ratchet wheel 50 fixed in any suitable manner to the rock shaft. Rotation of this disk as indicated by the arrow in Fig. 9, for example, will increase the tension of the spring.

The pen bar referred to above is indicated 85 at 51 the same being preferably round in cross section and the same is carried parallel to the rock shaft and the vertical plane of the main carrier, but at considerable distance laterally thereof by means of a skeleton frame or grille comprising main and auxiliary bars 52 and 53, the latter bars constituting diagonal braces as will be understood from Fig. 1. The inner ends of the bars 52 are fixed upon the squared ends 45 95 of the rock shaft, and the outer ends of the said bars are rigidly connected to the pen bar by means of clamps 54. The pen bar and grille connected as indicated to the rock shaft tend to be elevated by the action 100 of the springs 47 and the greater the tension of the springs the greater the tendency would be for the pen bar to be elevated thereby. To one end of the pen bar 51 is secured the master pen 55 by means of a 105 clamp 56. The preferred construction of these clamps is indicated in Fig. 11, the same being formed preferably of sheet metal and having U-shaped members embracing the opposite sides of the pen bar and held in place by a set screw 57. The clamp also includes a bracket 58 having a hole through which the pen projects and is adjustable as to elevation by means of nuts 59 threaded upon the holder. See Fig. 10. The master 110 pen 55 has clamped to its lower end a rigid arm 60 having a ball socket 61 at its free end in which is fitted a handle 62 through a ball 63 whereby the master pen is adapted to be manipulated. Any convenient number 115 of auxiliary pens 64 are connected to the pen bar 51 by clamping means preferably of the same character indicated in Fig. 11 and described above. In my extensive experience with these machines I find that a suitable 120 type of pen point is one in which a modicum of ink is carried directly therein in a pocket as indicated at 65, the supply being easily replenished by dipping the pens into open topped ink wells, an operation easily per- 125 130

formed through the manipulation at the handle 62. The pens are easily adjusted up or down through the brackets 58 or around their axes so as to adapt them to the desired work and when so adjusted are locked rigidly in place and swing bodily with the pen bar and grille 52 universally upon the surface of the documents or papers being signed. The carrier is movable longitudinally of the carrier frame 21 without material resistance by reason of the anti-friction balls 42 while the weight of the pen bar and parts associated therewith is nearly all counterbalanced by the springs 47, at least to the extent that only enough effective weight remains in the pens for ordinary writing operation. The character of the grille and associated parts is such, however, that the operator by depressing the master pen to make a heavier stroke will produce a similar stroke at each of the other or auxiliary pens. By providing separate springs 47 it is expedient to counterbalance the end of the grille remote from the operator's hand more or less than the end adjacent to his hand, if desired.

66 indicates a guide bar of angle structure in cross section connected by means of a pair of links 67 of equal length to a pair of brackets 68 adjacent to the carrier frame 21. These brackets 68 provide vertical pivots at the same distance from the carrier frame around which the links 67 and the guide bar 66 are adapted to be adjusted and locked by means of thumb nuts 69 or their equivalent so as to determine the distance of the guide bar laterally from the vertical plane of the carrier frame.

70 indicates a clamp bar secured to the guide bar 66 and having a series of laterally projecting fingers 71 secured in any suitable manner thereto, the design being for one of the fingers to lie flat upon the paper just above where the signature is to be made by each of the pens. The clamp bar may have substantial weight in itself or in connection with the guide bar to hold the papers flat and firm, or the links 67 may be in the nature of springs to serve the same purpose either alone or in connection with the weight of the bars just referred to. As will be obvious from Fig. 1 a series of documents to be similarly and simultaneously signed may be arranged upon the base and held in proper alignment with one another by means of the clamp bar and parts to which the clamp bar is connected, the adjustment of the guide bar lengthwise of the machine determining the space between the several fingers 71 and the field of operation of the pens. The grasping and manipulation of the handle 62 will then result in the writing of the multiple signatures in a manner very similar to the operation of an ordinary single pen.

Referring now to the modification of Figs. 12 and 13 it will be noted that the peculiar construction of the carrier renders it a matter of convenience to adapt the machine for double the number of signatures that would be provided for by the form shown in Fig. 1. That is to say without material alteration in the carrier frame 21 the heads 39 and 40 are adapted to have lugs 43 projecting from both sides thereof in which a pair of rock shafts 44 may be journaled parallel to the vertical plane of the frame 21. To each of these rock shafts is connected a grille or its equivalent supporting a pen bar 51 resiliently by means of the adjustable springs 47 in the manner already explained in connection with Fig. 1. Obviously the guide bar 66 and its associated parts would be duplicated in this form of the invention. Hence in the form indicated ten signatures may be written simultaneously instead of five. Since the pens are all intended to be manipulated from the master pen or handle 62 some suitable means must be provided to control the grille and move the pen bar from the one to which the master pen is connected. As shown in Fig. 13 therefore I provide pairs of intermeshing gear segments 72 clamped to the respective rock shafts 44. By virtue of these gear segments the elevation of one of the pen bars will be transmitted to the other pen bar and to a similar extent.

I claim:

1. In a multiple signature machine, the combination with a base having a pair of parallel slots formed therein, a pair of track ways in each slot and arranged in a vertical plane, a carrier frame lying in a vertical plane perpendicular to the planes of the track ways aforesaid, a carriage rigidly connected to each end of the carrier frame and mounted for anti-friction reciprocation in the adjacent pair of track ways providing for free movement of the carrier frame bodily laterally, carrier devices mounted for anti-friction reciprocation longitudinally of the carrier frame as well as laterally with the carrier frame, and a plurality of pens carried by the carrier and adapted for simultaneous and similar manipulation.

2. In a multiple signature machine, the combination of a base, a plurality of pairs of track ways carried by the base in vertical parallel planes, said track ways having upper and lower opposed V grooves, a main carrier frame above the base and extending from one pair of track ways to the other, a carriage movable between the track ways of each pair, anti-friction balls extending from the carriage in the V grooves and the track ways providing for free movement of the carriages lengthwise of the pairs of track ways, hangers rigidly connecting the ends of the carrier frame to the carriages

- providing for free movement of the carrier frame with the carriages to prevent twisting or binding action of the carrier frame, a series of pens, supporting means for the pens holding them all in fixed relation to one another, and means supporting the pen supports for movement longitudinally of the carrier frame and for up and down movement with respect to the base.
3. In a multiple signature machine, the combination of a main carrier frame comprising upper and lower parallel bars and means connecting the ends of one bar to the ends of the other bar, means supporting the carrier frame to maintain it positively in a vertical plane to permit free movement thereof laterally of said plane in either direction, a pen bar, a plurality of pens carried by the pen bar in fixed relation to one another, and supporting means for the pen bar carried within the carrier frame and movable freely longitudinally thereof.
4. In a multiple signature machine, the combination of a base, a carrier frame comprising upper and lower parallel bars, means connecting the carrier frame anti-frictionally with the base and providing for free movement of the carrier frame laterally in either direction from a vertical plane, upper and lower track ways carried by the carrier frame between the bars thereof and lying in the plane aforesaid, said track ways having upper and lower opposed V grooves, a carrier comprising a rock shaft and a plurality of heads to which the rock shaft is journaled, anti-friction balls carried by the heads and movable in said V grooves of the track ways, a series of pens and supporting means for the pens connected to said rock shaft and holding the pens in positive fixed relation to one another.
5. In a multiple signature machine, the combination of a carrier frame, means to hold said carrier frame in a vertical plane and permit movement laterally thereof in either direction, a shaft, means to support said shaft upon the carrier frame providing for free endwise movement thereof in either direction, a series of pens, supporting means for the pens serving to hold the pens in fixed relation to one another, and adjustable counterbalance devices associated with the shaft acting upon the pen supporting means serving to tend to lift the pens.
6. In a multiple signature machine, the combination of a base, two pairs of parallel track ways carried by the base in parallel vertical planes, each pair of track ways having upper and lower V grooves, a carrier frame extending between the vertical planes aforesaid, a carriage mounted between the grooved track ways of each pair of tracks and composed of a pair of bars fastened together, a series of anti-friction balls carried by the carriage, a spacer for the balls comprising a channel member having upper and lower parallel flanges through which the balls project into the grooves and track ways, said spacer being held in place loosely by the balls, hangers rigidly connecting the ends of the carrier frame to the respective carriages, a series of pens and supporting means for the pens mounted for free longitudinal movement along the carrier frame longitudinally of the track ways.
7. In a multiple signature machine, the combination of a base, a carrier frame supported in a vertical plane above the base and movable bodily laterally of said plane in either direction over the base, a carrier movable longitudinally of the frame and including a rock shaft having its axis fixed with respect to the other parts of the carrier and parallel to the plane of the carrier frame, a series of pens, pen supporting means holding the pens in fixed relation to one another and rigidly connected to the rock shaft, and a pair of independently adjustable counterbalance springs connected to the rock shaft and the other parts of the carrier and tending to turn the rock shaft and pen supporting means around the axis of the rock shaft.
8. In a multiple signature machine, the combination of a base, a carrier frame mounted above the base, means acting between the base and the carrier frame to maintain the carrier frame in a vertical plane and provide for free lateral movement thereof in either direction through the plane, a carrier movable freely longitudinally of the carrier frame and including a rock shaft whose axis is at one side of and parallel to the vertical plane of the carrier, a series of pens, pen supporting means holding the pens in fixed relation to one another and fixed to the rock shaft, a counterbalance spring surrounding the rock shaft, one end of the spring being secured to that part of the carrier to which the rock shaft is journaled, a disk journaled upon the rock shaft to which the opposite end of the spring is secured, said disk being movable around the rock shaft to vary the tension of the spring, and means acting between the disk and the rock shaft to determine the extent of such rotation and tension adjustment.
9. In a multiple signature machine, the combination of a carrier frame comprising upper and lower parallel bars, means to hold said bars in a certain plane, upper and lower parallel track ways carried by and between said bars, certain of said track ways being adjustable in said plane toward the other track ways, said track ways comprising opposed V grooves, a carrier arranged between and reciprocating along said track ways and including anti-friction

balls extending into the V grooves of the track ways, a series of pens, and supporting means for the pens holding them in fixed relation to one another and supported upon 5 and movable with said carrier.

10. In a multiple signature machine, the combination with a series of pens and a pen bar for holding all of them, of a series of pen brackets for the respective pens, 10 each pen bracket comprising a clamp for connection to the bar and a member having a hole through which the pen projects, and means coöperating with each pen serving to determine the up and down adjustment 15 of such pen with respect to the bracket.

11. In a multiple signature machine, the combination of a base, a series of pens and supporting means for the pens serving to hold the same in definite relation to one 20 another for universal movement over the base, of combined guiding and clamping means coöperating with the documents to be signed by the several pens, said combined means including a guide bar, adjustable 25 means connecting the same to the base and

serving to hold it always parallel to itself, and a series of parallel fingers, one for each pen, and serving to hold the documents flat and in fixed relative positions upon the base adjacent to the field of operation of the several pens. 30

12. In a multiple signature machine, the combination of a base, a carrier frame, means coöperating with the base to hold the carrier frame in a vertical plane and providing 35 all movements of the frame in directions lateral in either direction to said plane, a carrier mounted for anti-friction reciprocatory movement lengthwise of the frame, said carrier including a pair of heads and 40 a pair of shafts carried by the heads on opposite sides of and parallel to the plane of the carrier frame, pen supporting means connected to the rock shafts and movable upwardly from the base around the axes of 45 the shafts, and means coupling the shafts together for simultaneous rotation in opposite directions.

WILLIAM FRANK WILLIAMS.
